UNITED STATES PATENT OFFICE.

WILLIAM D. ADDISON, OF MANNING, IOWA.

AUTOMOBILE DRAFT-CONTROLLER.

1,284,030.

Specification of Letters Patent.

Patented Nov. 5, 1918.

Application filed May 15, 1917. Serial No. 168,702.

To all whom it may concern:

Be it known that I, WILLIAM D. ADDISON, a citizen of the United States, residing at Manning, in the county of Carroll and State of Iowa, have invented certain new and useful Improvements in Automobile Draft-Controllers, of which the following is a specification.

This invention relates to an improved draft controlling or cooling device for automobiles.

The main object of this invention is to provide a simple, durable, economical and efficient device which will readily serve to cool the water in the radiator, and when desired will retain the heat within the hood and radiator so as to prevent the freezing of the water and radiator.

Another object of the invention is to provide a practical device having ice cutting means connected therewith in order to insure its successful operation when driving against a blizzard by day or night, and when the climatic conditions are such that snow quickly melts and is also readily frozen thus making my improved device operative at all times and under all climatic conditions.

The foregoing and such other objects as may appear from the ensuing description are attained by the novel features of construction, combination, location and arrangement of parts hereinafter more fully described, illustrated in the accompanying drawings and particularly pointed out in the claims appended hereto, it being understood that slight changes in the form, proportions, and minor details of the construction may be resorted to without departing from the spirit or sacrificing any of the advantages of the invention.

In the accompanying drawings which form a part of this specification it will be seen that:

45 Figure 1, is a perspective view of the improved device embodying my invention.

Fig. 2, is a longitudinal sectional view taken through the hood and dash of an automobile, with my improvements attached thereto.

Fig. 3, is a front elevation of the inner draft oscillating wheel.

Fig. 4, is a front elevation of the outer draft oscillating wheel, showing the panels of the inner wheel partly closing the open-

ings therein and overlapping the panels of the outer wheel.

Fig. 5, is an enlarged view showing in rear elevation a portion of the dash at the rear end of the hood with the hand and foot operating means secured thereto, and

Fig. 6, is an enlarged perspective view of one of the ice cutting knives.

Similar numerals of reference are employed to designate corresponding parts throughout the several figures of the drawings.

In the embodiment of this invention as illustrated and which shows a preferred construction, the numeral 1 designates the hood member of an automobile, preferably made of sheet steel and adapted to cover any suitable type or construction of radiator (not shown), 2 the dash member secured at the rear end portion of the hood, and 3 indicates a metallic plate or frame suitably secured at the front portion of the hood, said plate or frame having four openings 4 formed therethrough for the free admission of cold air within the hood. Secured to the front face portion of the plate or frame 3, by a suitable rivet 5 is an inner oscillating circular draft wheel 6, and an outer oscillating circular draft wheel 7, the outer peripheral edges of both wheels being held in proper relationship to the frame by a plurality of ice cutting devices 8, which are suitably secured to the front face of the said plate or frame, as clearly shown in Fig. 1. Both the inner and outer draft wheels are provided with four openings adapted to correspond with the size of the openings 4, formed in the frame, the inner wheel 6 having four integral panels 9, and the outer wheel 7 being provided with four integral panels 10, said panels serving jointly to close or cover the openings 4 when properly oscillated or extended. Each of the panels of both wheels are provided with cutting edges 11, adapted to remove or cut away the snow and ice when the wheels are oscillated, and the inner wheel 6 is provided with an integral peripheral extension 12, having a projecting stud 13 formed at its upper end portion, and a projecting stud 14 formed at its lower end portion, both the upper and lower edges of said extension having a cutting edge 15 similar to the cutting edges of the ice cutting knives, while the outer oscillating draft wheel 7 is provided with a

100
105
110

plurality of integral ice cutting knives 16 and an integral extension 17 formed on its periphery which is adapted to contact with the projecting studs 13 and 14 and thereby 5 oscillate the inner wheel in unison therewith when the said outer wheel is given an oscillating movement to either open or close the draft openings.

Suitably secured at 18, to one of the panels 10 of the outer wheel 7, is a cord, wire or cable 18', which is passed downward and over a pulley 19 carried by the front plate or member 3, thence within the hood where it is secured to an eye 20 formed on the front end portion of a bar or rod 21, which passes through a cylinder 22 suitably arranged within the hood, the rear end portion of said rod 21 passing through an opening formed in the dash 2, and terminating with an upper 15 integral handle portion 23, and a downwardly projecting portion 24, whereby said rod may be easily manipulated by either the hand or foot, and the lower rear portion of said rod is provided with a series of notches 25, adapted to engage the upward extending tongue 26, formed on the semi-circular plate 27, carried by the dash, thereby 20 securing the said rod in its adjusted position.

45 The pulley 19, and the opening therefor in the front plate or frame 3, is protected from the weather by a shield 28 suitably secured to the outer face of the plate or frame 3 as shown in Figs. 1 and 2.

50 As will be seen by reference to Fig. 1, the drafts are shown in the open position creating a free inlet for the cool air, said open position being caused by the rearward movement of the rod 21 by the driver, which 40 movement causes a downward pull on the cable 18' thus forcing the extension 17, on the outer draft wheel 7, to contact with the stud 13 carried by the inner wheel 6, and carry the inner wheel with the outer wheel 45 until the stud 13 contacts with an upper ice cutting device 8, which constitutes a stop of the further movement of said draft wheels.

The closing operation for the said draft is 55 performed by a spring 29, the upper end of said spring being secured to a hook or staple 30 secured to one of the panels of the outer draft wheel, while its lower end is suitably secured to a hook 31 attached to the bottom portion of the front plate or frame 3. It 50 will be readily perceived that when the bar or rod 21 is lifted by the hand or foot of the driver from its engagement with the tongue 26, the tension of the spring 29 will immediately cause a downward movement of the outer draft wheel until its peripheral extension 17, contacts with the stud 14 carried by the inner draft wheel, and thus move the inner draft wheel in unison therewith until the stud 14, contacts with the lower ice cutting device 8, thereby constituting a stop of the

further oscillating movement of both draft wheels, arresting their further movement, and closing the draft openings 4 in the front plate or frame.

While one of the objects of my improved 70 draft device is to retain the heat within the hood during extremely cold weather, and thereby prevent the freezing of the water in the radiator, at the same time through the operation of the oscillating draft wheels, it 75 is necessary to make frequent changes in order to cool the radiator during travel over bad roads, hence to make my invention efficient and practical for night driving, I have provided the draft device with a cylinder 22, 80 which contains a piston 32, through which and both ends of the cylinder runs a rod 21 said rod being fixedly secured to the piston. The said cylinder is provided at one end with an inlet tube 33, and toward its other 85 end is provided with an outlet tube 34, the said inlet tube having connected therewith a steam hose 35, which hose is suitably connected at its other end with the overflow pipe of a radiator (not shown). The function of this equipment is when the water in the radiator is boiling the steam and hot water will enter the cylinder through the steam hose and inlet, and force the piston toward the opposite end of the cylinder beyond the outlet tube 34, thereby carrying the manipulating rod 21 with it during its rearward movement thus opening the draft through the medium of the means herein-before described, and thereby immediately 100 reducing the pressure within the cylinder and allowing the steam and hot water to escape through the outlet tube 34. By the action of this automatic arrangement the notched bar 21 locks itself to the tongue 26, 105 formed on the plate 27, and when it is desired to close the draft it is simply necessary for the driver to trip the lock with his toe or hand, when by means of the spring herein referred to, the draft openings will immediately 110 become closed.

It will be readily understood that in some makes of automobiles I may prefer to dispense with the use of a spring for performing the closing operation of the draft, and use a weight attached to or carried by a panel near the staple or hook 30.

It will be perceived that the four large openings formed in the front plate or frame for the free admission of air into the hood, 120 are of less area than the eight panels carried by the two oscillating draft wheels which it takes to cover the four openings, but this arrangement permits a larger volume of air to circulate through the radiator than a single wheel, since in a single wheel the panels would be equal in size to the openings and an increased number of panels would not increase the volume of air admitted, although an increased number of 125 130

draft wheels would increase the volume of air permitted to circulate through the radiator.

By reference to Fig. 6 will be seen an enlarged view of one of the ice cutting knives 8, provided with a vertical extension 36, which is fixedly secured to the front face of the front plate or frame 3, and is provided with a right angle forward extension 37, 10 adapted to overlap the peripheral portion of both the inner and outer draft wheels, and terminating in a downward extension 38, provided with ice cutting edges and which overlap the front face of the outer peripheral portion of the outer draft wheel, 15 as clearly shown in Fig. 1.

Having thus described my invention what I claim and desire to secure by Letters Patent is:—

- 20 1. A draft controlling device for automobiles comprising a front plate provided with a plurality of openings therethrough, a plurality of draft wheels secured to said plate, each of said wheels having a peripheral extension adapted to contact with each other, and move the wheels in unison.
- 25 2. A draft controlling device for automobiles comprising a front plate having a plurality of openings therethrough, a plurality of draft wheels secured to said plate, each of said wheels having a series of integral panels, the inner wheel having a peripheral extension provided with projecting studs and the outer wheel having a peripheral extension adapted to contact with said studs and move the said wheels in unison.
- 30 3. A draft controlling device for automobiles comprising a front plate having four

draft openings therethrough, a plurality of oscillating draft wheels secured to said plate, each wheel having a series of integral panels, the outer wheel having a series of integral ice cutters and an integral peripheral extension and projections formed on the inner wheel whereby the wheels are 45 moved in unison to open or close said openings.

4. A draft controlling device for automobiles comprising a front plate having four openings therethrough, an inner and an outer oscillating draft wheel secured to said plate provided with means for closing said openings when oscillated in unison, the inner wheel having a peripheral extension provided with two projecting studs, and the outer wheel having a peripheral extension adapted to contact with said studs.

5. A draft controlling device for automobiles comprising a front plate having a plurality of openings therethrough, a plurality of draft wheels secured to said plate, the inner wheel having a peripheral extension provided with projecting studs adapted to engage with a peripheral extension in the outer wheel, and a series of integral ice cutters formed on the said outer wheel.

6. A draft controlling device for automobiles comprising a front plate having a plurality of openings therethrough, an inner and an outer draft wheel secured to said plate, each wheel having a series of integral panels, and a peripheral extension formed on each wheel adapted to contact with each other and move the wheels in unison.

WILLIAM D. ADDISON.
